DESIGN FOR A DRESS

Shirley Aronoff, New York, N. Y.

Application February 29, 1940, Serial No. 90,587

Term of patent 3½ years

To all whom it may concern:

Be it known that I, Shirley Aronoff, a citizen of the United States and a resident of the city of New York, in the county of Kings and State of New York, have invented a new, original, and ornamental Design for a Dress, of which the following is a specification, reference being had to the accompanying drawing, forming a part thereof.

Fig. 1 is a front view of a dress showing my new design.

Fig. 2 is a rear view of the dress as shown in Fig. 1.

The characteristic feature of my design resides in the combination on the specific dress disclosed of the pleated trimming around the neck line and on the sleeves in association with the wide gathered girdle and sash, as shown.

I claim:

The ornamental design for a dress, substantially as shown and described.

SHIRLEY ARONOFF.
